Letters Patent No 1083. Dated Feby 15 1859.

The Schedule referred to in these Letters Patent and making part of the same.

To all whom it may concern:

Be it known that I, Clemir J. Ney, of Lowell in the County of Middlesex and State of Massachusetts have originated and designed a new pattern for Carpets or other fabrics, of which the following is a full clear and exact description, reference being had to the accompanying drawings making part of this Specification.

1 and 2. in the corners are quarters of a star the interior of which is formed of small keywork A. running from the center to the circumference of the stars.

The points of the stars are bordered by small circles f. and are surrounded by belts formed of small dots diminishing in size from the inside to the outside edges.

In the corners 3 and 4 are flowers g. and leaves h. resting upon the vined leaves c. which slightly overlap the belts B. of the stars.

The colors employed for the different portions of the design may be varied to suit the taste and wishes of the manufacturer.
